UNITED STATES PATENT OFFICE.

RICHARD W. RUNGE, OF OSHKOSH, WISCONSIN, ASSIGNOR TO LEACH COMPANY, OF OSHKOSH, WISCONSIN, A CORPORATION OF WISCONSIN.

POWER BOOM-SWINGING MECHANISM.

Application filed July 17, 1925. Serial No. 44,252.

This invention is concerned with the manipulation of the massive booms with which street pavers and various other large machines are equipped.

5 Heretofore it has been the practice to swing such booms from one position to another by hand, owing to the fact that ordinary power operated mechanisms will not withstand without injury the severe shocks 10 set up therein by the resistance of the boom in being started or stopped.

The principal object of the invention is to provide a power operated boom-swinging mechanism which will absorb within the same all of the severe shocks encountered in swinging a boom from one position to another.

Other objects and advantages not specifically referred to in this disclosure will be appreciated by those skilled in the art upon a full comprehension of the construction, arrangement and manner of operation of the mechanism.

For the purpose of exemplification, one embodiment of the invention is presented in the accompanying drawings and in the following detailed description, but as numerous other modified embodiments are also obviously within the purview of the invention, the form here presented is not to be considered as limiting the spirit of the invention short of its intended scope as defined in the claims.

In the drawings—

35 Fig. 1 is a fragmentary side view of a street paver or other machine equipped with the mechanism of the invention;

Fig. 2 is a plan view of the mechanism; and

40 Fig. 3 is a section taken vertically through the center of the mechanism.

It will be observed in the drawings that the boom-swinging mechanism of the invention is illustrated in association with a 45 road paver or other large machine having a vertically extending frame portion 10 at one end of the same. A bracket 11 projects horizontally from the frame portion 10, and terminates in a suitably lined bearing collar 12 in which a vertically extending trunnion 13 is journalled. One end of the trunnion 13 extends below the collar 12 of the bracket 11 and is there connected to the inner end of a massive boom 14 by a pivot pin 15 which is so 55 arranged as to permit the boom to be swung

in a vertical plane about its point of attachment with the trunnion. The other end of the trunnion 13 extends above the collar 12 and is there connected with a spider 16 by a number of bolts 17.

A gear 18 is journalled on the trunnion 13 between the spider 16 and the collar 12, and is yieldably connected with the spider by two sets of interleaved friction disks 19 and 20 which are keyed respectively to the gear 60 and the spider. The gear 18 is oscillated in either direction by a suitable power train which will be hereinafter described. The two sets of disks 19 and 20 are pressed into frictional engagement with each other by a 65 number of coil springs 21 which are held in compressed condition between the uppermost disk 20 and an annular plate 22 in the spider 12; and the plate 22 is adjustably positioned toward or away from the uppermost disk 20 by a number of set screws 23 which are mounted in the spider. The disks and associated parts may be advantageously housed within a sheet metal casing 24 of 70 cylindrical form.

75 The multiple disk arrangement herein described provides a yieldable but effective torque transmitting connection from the gear 18 to the boom 14, which connection will cause the boom to move as a unit with 80 the gear when no undue resistance is offered by the boom, but will permit momentary slippage between the same when any high resistance is abruptly offered by the boom due to the inertia in starting to swing or to 85 the momentum in stopping.

90 The power train for oscillating the gear 18 in either direction to swing the boom may 95 obviously assume any one of several forms, but is herein disclosed as including a worm 25 which is meshed with the gear 18 and is secured on a shaft 26. The shaft 26 is rotated in either direction by two opposite rotating gears 27 and 28 which are journalled 100 on the shaft and may be alternately clutched to the same. The gears 27 and 28 may be clutched to the shaft 26 by being clamped frictionally between two disks 29 and 30 which are secured to the shaft, the disks 30 being shifted axially of the shaft by links 31 105 which are carried by sleeves 32 on the shaft, and the sleeves 32 in turn being shifted by suitably fulcrumed shifting yokes 33. The yokes 33 may be coupled together by links 34 110 in order to permit operation of the same in 110

unison from a control handle 35 located at one side of the machine in a position convenient to the operator.

The gears 27 and 28 are rotated in opposite directions by two gears 36 and 37 with which they respectively mesh. The gears 36 and 37 are secured to two axially aligned shafts 38 and 39 which are provided at adjacent ends with opposed bevel gears 40 both of which mesh with a bevel gear 41 on a shaft 42. The shaft 42 is continuously rotated in one direction from a suitable power source mounted on the machine.

It will be evident from the construction above described that when the control handle 35 is in a neutral position, both of the gears 27 and 28 will rotate freely on the shaft 26, and the worm 25 in mesh with the gear 18 will remain at rest; that when the handle 35 is moved one way, the gear 27 only will be clutched to the shaft 26, and the worm 25 will rotate in one direction to oscillate the gear 18 slowly and cause the boom to swing as soon as the shock on the power train caused by the inertia of the boom in starting has been absorbed by the connection between the gear 18 and the boom; and that when the handle 35 is moved the other way, the boom will be swung in the opposite direction.

I claim:

1. A mechanism for swinging a pivotally mounted boom, including a power operated gear mounted in axial alignment with the pivotal axis of the boom, a set of friction disks in non-rotatable association with the gear, another coacting set of friction disks in non-rotatable association with the boom, and springs for pressing the disks of one set into frictional engagement with the disks of the other to effect a frictional torque transmitting connection between the gear and the boom.

2. A mechanism for swinging a pivotally

mounted boom, including a power operated gear mounted in axial alignment with the pivotal axis of the boom, a spider fixedly connected with the boom in axial alignment with the pivotal axis of the same, a set of friction disks in non-rotatable association with the gear, another coacting set of friction disks in non-rotatable association with the spider, springs for pressing the disks of one set into frictional engagement with the disks of the other to effect a frictional torque transmitting connection between the gear and the boom, and means for adjusting the amount of pressure applied to the disks by the springs.

3. A mechanism for swinging a pivotally mounted boom, including a bracket having a collar from which the boom is supported, a trunnion journaled in the collar and secured to the boom, a spider secured to the trunnion and provided with a peripheral flange, a power operated gear journaled on the trunnion, a thrust ring positioned about the spider in spaced relation to the flange, two interleaved sets of friction disks connected respectively with the spider and the gear, springs interposed between the friction disks and the ring, and means interposed between the ring and the flange for adjusting the position of the former toward or away from the latter.

4. A mechanism for swinging a pivotally mounted boom, including a power-operated gear mounted in axial alignment with the pivotal axis of the boom, a friction disk connected with the gear, another coacting friction disk connected with the boom, and springs for pressing the disks into frictional engagement with each other to effect a frictional torque transmitting connection between the gear and the boom.

In testimony whereof I have hereunto subscribed my name.

RICHARD W. RUNGE.
